UNITED STATES PATENT OFFICE.

FRANK J. MONZ, OF NEW HAVEN, CONNECTICUT, ASSIGNOR TO THE
SARGENT & COMPANY, OF CONNECTICUT.

METHOD OF MAKING WROUGHT-METAL HOOKS.

SPECIFICATION forming part of Letters Patent No. 624,067, dated May 2, 1899.

Application filed August 24, 1897. Serial No. 649,340. (No model.)

To all whom it may concern:

Be it known that I, FRANK J. MONZ, a citizen of the United States, and a resident of the city of New Haven, county of New Haven, 5 and State of Connecticut, have invented a new and useful Improvement in Wrought-Metal Hooks, fully described and set forth in the following specification, taken in connection with the accompanying drawings, in 10 which like letters of reference represent like parts in all the figures.

Figure 1 is a side elevation of the blank from which the hook is formed; Fig. 2, the same partially operated upon; Fig. 3, a detail view of the plate to which the hook is secured, and Fig. 4 a side elevation of the hook as finally formed and assembled.

This invention consists in a novel and efficient method of constructing hooks, more 20 particularly that class of hooks wherein a plate for securing the hook to a shelf or other article is formed separate from the hook and united thereto by rivets, screws, or other means. In this class of hooks an extra amount 25 of metal is required at the angle of the blank to form the rivets and other portions of the hook proper where it is attached to the plate. It has been usual in forming hooks of this description to draw or taper the blank or rod 30 prior to bending and flattening the same to shape in such a way that the rod will be of greater thickness at one portion than at another, so that at the thickened portion there will be enough metal to be subsequently 35 formed into the studs, rivets, &c., for attaching the hook to the plate. The present invention obviates the necessity of such previous drawing or tapering by obtaining the necessary amount of metal for the studs or 40 rivets from an increased length of the wire instead of from an increased thickness, and to this end when the angle of the blank is formed it is so arranged that the length of the wire included therein will be greater than the length 45 of the corresponding portion of the finished product between the same points on the blank.

A represents a wrought-metal hook formed from a blank, as shown in Fig. 1, bent up to form an angle α , the blank being throughout 50 out of equal diameter except where the heads

a' are formed integral therewith or united thereto. A flat plate C, of any desired outline, is stamped out, as shown in Fig. 3, with screw-holes c and two circular perforations c' in a vertical line with each other. To unite 55 the hook A to the plate C, it is necessary that the angle α be flattened and that studs b or other means be provided for fastening the plate C and hook A together. This is accomplished by swaging the blank A (shown in 60 Fig. 1) in a press, so that the metal in the angle α is forced to assume the form shown in Fig. 2, wherein a vertical semicylindrical portion B unites the upper and lower arms D and D' of the hook and has on its flat side 65 two laterally-projecting studs b , corresponding to the perforations c' on the plate C. As the portion B is of greater diameter when taken through the studs b than the arm D and D', the extra metal necessary for its formation is obtained by constructing the angle α , Fig. 1, of such depth that although it is 70 of equal diameter with the rest of the shank there will be sufficient metal between the points x and x' to form, upon pressure, the 75 portion B and studs b . The arms D and D' are held by proper mechanism against longitudinal movement, and pressure is exerted at the apex of the angle to reduce the length 80 of the angle portion of the rod, and thereby 85 crowd the metal on either side between the apex and the rigidly-held arms to greater width, which widened portion is formed into the semicylindrical portion B, with the lateral studs b on the flat side thereof. By this 90 means a blank of uniform thickness may be utilized to form the hook and the necessity of drawing the blank to different diameters obviated. The arms D and D' may be subsequently curved, as shown in Fig. 4, and the 95 hook and plate assembled by inserting the studs b in the perforations c' and riveting them down to secure the plate to the hook.

Having now described my invention, what I claim, and desire to secure by Letters Patent, is—

The herein-described method of making a wrought-metal hook, consisting of bending a wire of uniform diameter throughout its shank into an angular form, the length of the 100

shank being greater than its length in the finished article; reducing the length of the angular portion of the shank by longitudinal pressure and forming at the reduced middle

5 part a semicylindrical portion having on its flat side laterally-projecting studs, the extra metal for the studs being obtained by the reduction of the length of the article; and uniting to said semicylindrical portion by means

of said studs a plate for attaching the hook to the desired article, substantially as described.

In witness whereof I have hereunto set my hand the 23d day of August, A. D. 1897.

FRANK J. MONZ.
